US00D345794S

United States Patent [19]**Hood et al.****[11] Patent Number: Des. 345,794****[45] Date of Patent: ** Apr. 5, 1994****[54] AN ULTRASONIC CUTTING TOOL FOR MEDICAL USE****[75] Inventors: Larry I. Hood, Laguna Hills; Gregg Hughes, El Toro, both of Calif.****[73] Assignee: Advanced Osseous Technologies, Inc., Aliso Viejo, Calif.****[**] Term: 14 Years****[21] Appl. No.: 714,091****[22] Filed: Jun. 11, 1991****[52] U.S. Cl. .... D24/144; D24/146****[58] Field of Search .... D8/70, 47, 98, 101; 30/167, 168, 169; 128/24 A; 606/79, 83, 169; 604/22; 408/36, 62, 230; 175/715, 8; D24/146, 147, 170, 231; D15/138, 139; D19/35****[56] References Cited****U.S. PATENT DOCUMENTS**
